(57) **CLAIM**

The ornamental design for a fuel tank repair ring, as shown and described.

DESCRIPTION

FIG. 1 is a perspective view of a fuel tank repair ring according to our invention;

FIG. 2 is a front elevation view of our fuel tank repair ring shown in FIG. 1;

FIG. 3 is a rear elevation view of our fuel tank repair ring shown in FIG. 1;

FIG. 4 is a left side elevation view of our fuel tank repair ring shown in FIG. 1;

FIG. 5 is a right side elevation view of our fuel tank repair ring shown in FIG. 1;

FIG. 6 is a top plan view of our fuel tank repair ring shown in FIG. 1;

FIG. 7 is a bottom plan view of our fuel tank repair ring shown in FIG. 1; and,

FIG. 8 is section view along the line 8-8 in FIG. 6 of our fuel tank repair ring shown in FIG. 1.

The broken lines in the above figures show portions of our fuel tank repair ring that form no part of our claimed design.

1 Claim, 6 Drawing Sheets
